LOCK AND LATCH

Norman B. Hurd, Newington, Conn., assignor to
The American Hardware Corporation, New
Britain, Conn., a Corporation of Connecticut

Application March 2, 1933. Serial No. 659,254

12 Claims. (Cl. 70—47)

My invention relates to improvements in locks and latches, particularly of that type in which the latch-bolt or dead-bolt, or both, may be operated by means of the so-called cylinder lock that is detachably connected to the outdoor side of the lock case. My object is to provide means whereby when the cylinder lock is attached to the lock case by the usual screw threaded connection, it may be locked thereto in such a manner that it cannot be removed therefrom, excepting by the use of a special means, such as a special key different from the usual pass key or master key. By thus guarding against removal of the cylinder lock from the lock case, excepting by an authorized person holding a proper key, certain methods of unlawful entry are prevented.

In the drawing—

Fig. 1 is a side elevation relatively enlarged showing a cylinder lock as applied to a portion of a lock case and locked against removal, certain portions being in section;

Fig. 2 is an elevation of the parts shown in Fig. 1, excepting the roll-back, and viewed from the right hand side;

Fig. 3 is a view similar to Fig. 1, showing certain parts in a different position and showing a different key from that shown in Fig. 1;

Fig. 4 is an elevation similar to Fig. 2 of the parts in the position shown in Fig. 3;

Fig. 5 is a section on the line 5—5 of Fig. 1, certain parts appearing in elevation;

Fig. 6 is a perspective view of a detail.

I have shown and shall describe only one particular form of my invention, and I desire it to be understood that it is susceptible of various modifications without departure from the spirit or scope thereof.

1 represents a portion of an ordinary lock case in which there is the usual threaded opening for receiving the usual threaded end of a cylinder lock body 2. It may be assumed that the lock case 1 is to contain the usual latch-bolt or dead-bolt, or both, with the well known appropriate parts associated therewith, and which are actuated by means of the usual roll-back 3' or spindle such as carried by or connected to the rotatable plug 3 of the cylinder lock. Such parts are too well known to require illustration or detailed description. The body 2 of a cylinder lock is threaded at its rear to screw into the opening in the lock case 1 in the usual way. 4—4 are the usual locking tumblers for the plug, operable by the regular pass or master key 5. 4' is a special tumbler that performs a

different function later described. This tumbler may be operated for mere plug unlocking purposes by the key 5, but is operable by a special key 6 in a different way and for a different purpose. Each pin tumbler may have the usual spring 60 impelled follower. 7 is a sleeve rotatably mounted on and near the rear end of the plug 3, said sleeve having a passage therethrough for, and normally in line with, the tumbler 4' and its follower. 8 is a coacting sleeve surrounding 65 the plug just to the rear of the sleeve 7. 7' is a shoulder on the edge of the sleeve 7 extending toward the sleeve 8 and into a recess in the latter, said recess being long enough so that the sleeve 7 may have slight independent rotary 70 movement relatively to sleeve 8 for the purpose later described. 8' is a nose on the periphery of the sleeve 8. At the back of the body 2 is a guideway in which I locate a slide 9, which overstands the sleeve 8, and which constitutes 75 one form of locking device for locking the cylinder lock body 2 to the lock case 1 so that it may not be unscrewed therefrom and removed, excepting it is first released by the use of said special key. 10 is a spring which normally 80 urges the locking slide 9 toward the sleeve 8. The inner end of the slide 9 has a shallow notch 9' and a deeper notch 9''. The sleeve 8 may be turned so that the nose 8' may be shifted into one or the other of said notches. When 85 the nose stands in the deep notch 9'', the locking device 9 will be retracted to its unlocking position, whereas when it stands in the shallow notch 9', the end of the slide will project outwardly into a notch or groove 1' in the threaded 90 edge of the passage through the lock case so that the cylinder lock body cannot be unscrewed and detached from said case at such a time. On the inside of the case 1, I may cast a boss 1'' that may have a long groove to receive the 95 end of the locking device so that the cylinder lock body may be screwed into the lock case more or less whereby said cylinder lock may be adjusted to doors of different thicknesses. When the regular key 5 is used, it will not shift 100 the tumbler 4' into the passage in sleeve 7, and consequently said sleeve will be held against turning in the body 2 by the end of the follower for the tumbler 4'. The plug 3 may be turned by a regular key 5 to operate the bolt 105 mechanism within the lock case 1, but that particular key will have no effect on the locking device 9. The special key 6 is so bitted and shaped at its inner end that it may extend sufficiently into the sleeve 7 to engage and lift the 110

tumbler 4' into the passage in the sleeve 7 and couple it to the plug, at the same time displacing the follower therein. This leaves said sleeve 7 free to be turned to the right or left with the plug. By turning this sleeve sufficiently, the shoulder 7' will engage with the shoulder at one or the other end of the recess in the sleeve 8 so that by continuing to turn said key 6 in the same direction, the sleeve 8 will be turned so as to move the nose 3' in a corresponding direction. When turned in one direction, the nose 3' will be moved toward and into the shallow notch 9', thus projecting the locking slide 9 outwardly to engage with the lock case 1 and thus prevent the cylinder lock body from being unscrewed therefrom and removed. When turned in an opposite direction, the nose 3' will be projected toward and into the deep notch 9'', whereupon the spring 10 will retract the slide and unlock the body 2 from the case 1 so far as concerns the locking device 9. When the device 9 has been thus set in one position or the other, the plug 3 may be turned back sufficiently far without disturbing the position of the sleeve 8, to permit said key to be withdrawn from the plug. In the particular form shown, the main function of the special key 6 is to merely control the locking device 9, but in this case it must be so bitted that it will operate the locking tumblers to release the plug 3, to permit the latter to be turned in one direction or the other for the aforesaid purpose. Ordinarily, cylinder lock bodies when secured to lock cases are held against looseness or turning therein by means of the well known long screw 11 carried by the lock case, the outer end of which (not shown) is accessible at the face-plate thereof, while the inner end extends into a longitudinal groove 2' in the side of the body 2. Manifestly, this alone will not prevent the cylinder lock from being removed from the case 1 when the door is opened because access may then be had to said screw. Since cylinder locks are sometimes removed for unlawful purposes, it is highly important to prevent such removal by any unauthorized person. The present invention makes the removal of the cylinder lock from the lock case impossible, since the locking device 9 is operable only by the use of a special key, and the mere backing off of the screw 11 is insufficient to fully release the cylinder lock so that it may be turned.

I claim:

1. A cylinder lock body threaded to engage by rotation a threaded opening in a lock case, a rotatable plug in said body, locking means carried by said body to engage said case to prevent the rotation of said cylinder lock therein, said locking means being operable by a special key insertable in said plug, said cylinder lock being operable by a different key insertable in said plug and without operating said locking means.
2. A lock, including a body threaded at its rear for attachment by rotation in a threaded opening in a lock case, and also including a rotatable plug and tumblers therefor, a locking device carried by said body and movable to a position to hold said body from rotation relatively thereto, said tumblers being operable by one key to permit rotation of the plug for normal lock operation only and being operable by a different key for operating said locking device to permit said cylinder lock to be rotated in said case and removed therefrom.
3. Means for locking a cylinder lock to a lock

case comprising a lock body screw threaded at its rear, and attachable and detachable to and from said case by rotation, a locking device adjacent the rear end and projectible beyond the side thereof to engage said case to prevent rotation, a rotatable member in said body, means to couple said member with said device, said member being operable for one purpose by one key independently of said coupling means, and being operable by a different key for another purpose dependently with said coupling means.

4. In a cylinder lock, a lock body attachable by rotation to a lock case, a laterally movable locking device therefore at the rear of the cylinder lock for engagement with said case to prevent rotation of said body therein, a rotatable plug, tumblers therefor, said tumblers being controlled and said plug being operable for door locking purposes by one key without operating said locking device, said tumblers being also controlled and said plug being operable by a different key for operating said locking device.

5. Means for attaching a cylinder lock to a lock case by rotation comprising a lock body screw threaded at its rear, a locking device adjacent the rear end and projectible beyond the side thereof into engagement with said case to prevent rotation, a rotatable member in said body, means to couple said member with said device, said member being operable for one purpose by one key independently of said coupling means and being operable by a different key for another purpose dependently with said coupling means, one of said tumblers comprising part of said coupling means.

6. Means for locking a cylinder lock to a lock case comprising, a body screw threaded at its rear to be attached to a lock case in a threaded opening in the latter, a rotatable plug in said body, tumblers and followers therefor, two coacting sleeves on said plug with means to permit limited rotary movement of one sleeve relatively to the other, one of said followers normally holding one sleeve against rotation with said plug, one of said tumblers being operable by a special key to displace said last mentioned follower and connect said sleeve to said plug for rotation, a locking device, the said other sleeve coacting therewith to move the same when the first sleeve is rotated with said plug.

7. Means for locking a cylinder lock to a lock case comprising, a body screw threaded at its rear to be attached to a lock case in a threaded opening in the latter, a rotatable plug in said body, tumblers and followers therefor, two coacting sleeves on said plug with means to permit limited rotary movement of one sleeve relatively to the other, one of said followers normally holding one sleeve against rotation with said plug, one of said tumblers being operable by a special key to displace said last mentioned follower and connect said sleeve to said plug for rotation, a locking device, the said other sleeve coacting therewith to project the same when the first sleeve is rotated with said plug, and a spring to retract said locking device.

8. In a cylinder lock, a body attachable to a door by rotation, a rotatable plug in said body, tumblers therefor, a locking device at the rear of said body to prevent rotation of said body in said door, coupling means between said plug and said locking device, said plug being operable by one key without operating said locking device, said coupling means being operable by a different key whereby movement of said plug

will be transmitted to said locking device to operate the same.

9. In a cylinder lock, a body attachable to a door by rotation, a rotatable plug, tumblers therefor, a locking device at the rear of said body to prevent rotation of said body in said door, coupling means between said plug and said locking device, said plug being operable by one key without operating said locking device, and being operable by a different key whereby movement of said plug will be transmitted to said locking device to project the same.

10. A lock including a body threaded at its rear for attachment by rotation in a threaded opening in a lock case, and also including a rotatable plug with tumblers therefor, and a locking device carried by said cylinder body for engagement with the lock case to hold said body from rotation relatively thereto, said tumblers being operable by one key to permit rotation of the plug for door locking purposes only and being operable by a different key to permit

rotation of said plug for the purpose of operating said locking member.

11. A cylinder lock having a body threaded to be engaged by rotation in a threaded opening in a lock case, a rotatable plug in said body, means carried by said cylinder lock and operable by one key insertable in said plug to prevent rotation of said cylinder lock in said case, and also operable by a different key insertable in said plug for another purpose without actuating said means.

12. In a structure of the character described, a cylinder lock, means to attach the same to and detach the same from a door by a rotary movement thereof, means carried by said cylinder lock and controlled by a key adaptable to said lock and movable in one direction to prevent rotation and detachment of said lock from said door and in another direction to permit rotation and detachment of said lock from said door.
